MACHINE FOR ASSEMBLING THE PARTS OF BUTT-HINGES AND THE LIKE.

1,006,698.

Specification of Letters Patent.

Patented Oct. 24, 1911.

Application filed February 18, 1911. Serial No. 609,335.

To all whom it may concern:

Be it known that we, HERMANN STELLER and RUDOLF PIEPENSTOCK, subjects of the Emperor of Germany, and both residents of 5 Oeckinghausen, near Karthausen, Westphalia, Germany, have invented a Machine for Assembling the Parts of Butt-Hinges and the Like, of which the following is a specification.

10 The present invention relates to a machine by means of which the parts of butt hinges as well as other hinges, and the like, are automatically assembled. The parts of the hinges, viz., the flaps, the pins and the 15 knobs are fed through inclined channels onto a table where, by means of rams and slides, the two flaps of the hinge are joined to their knobs and secured to the hinge pin. Finally, the completed hinge is automatically 20 expelled from the machine. All these operations are effected automatically and no other hand-work is required than the deposition of the parts into the feeding channels. Such deposition may, if desired, 25 also be automatically effected.

In the accompanying drawing the invention is illustrated, Figure 1 representing a plan of the machine, some parts thereof being shown by broken lines only, for the sake 30 of clearness, Fig. 2, a side view of the same, Fig. 3, a cross-section on the line A—A of Fig. 1, and Fig. 4, a view of one of the details of the machine.

The mechanical elements of the machine 35 are arranged on a table top 1 which is supported on legs 2. On said table top four rams 3, 4, 5 and 6 are arranged in horizontal position and in such a manner that each ram is parallel to another and in alinement with 40 a third. The rams are slidably guided by means of their holders in bed-plates 7 and are moved in axial direction by eccentrics 8 co-acting with springs 9. Rollers 17 on the ram-holders take the thrust of the eccentrics and reduce the friction. The eccentrics 45 are mounted on shafts 10 which are rotated by bevel gears 11 and 12, the latter gear being connected to a shaft 13 which in its turn is rotated by the driving shaft 14 through the medium of cog-wheels 15 and 16. On the ends opposite the bevel gears 11 the shafts 10 carry cams 18 which operate double-armed pivoted levers 19. The latter are connected to slides 21 and 22 which are

slidably guided on the table top at right angles to the rams. The slides are tensioned, together with the levers, by springs 23, and the levers engage the cams by means of rollers 20.

The various hinge-parts are fed onto the 60 table top by means of inclined feeding channels 24, 25, 26, 27 and 28 which in Fig. 1 are shown by broken lines only. Any known automatic device may, if desired, be provided for supplying the hinge-parts to the 65 channels. The channels are open at their lower ends so that the lowermost hinge-part always rests on the table top or on the special supporting plate provided thereon for the purpose. 70

The holder of the ram 5 has an off-set arm 31 connected thereto which arm, at the movement of the holder, engages the hinge-flap 32 protruding through the channel 27 and places the same in front of the slide 21. 75 Thereupon the latter moves and advances the flap so that its eye gets into alinement with the rams 3 and 5. These rams then approach one another, the former carrying with it a pin 30 from the feeding channel 80 28, and the latter a knob 29 from the channel 25. Both these elements are forced by the ram into the eye of the flap 32 and secured thereto, the knob with its stem and the pin with half its length. The slide 21 acts on 85 the flap by means of a U-shaped frame, the member 38 of which is disposed so as to move clear of the flap as long as no knob or pin is connected thereto. Down-turned lugs 39 (Fig. 4), however, while moving clear of the flap itself, engage the knob and the pin when these have been connected to the flap. After such connection, therefore, the flap will be advanced by the arm 38 so that the hinge pin gets into alinement with the rams 90 4 and 6. These rams, which have been at work meanwhile, now complete the hinge. An off-set arm 40, connected to the holder of the ram 4, engages the flap 32^a protruding through the end of the feeding channel 100 26 and passes the same within reach of the arm 41 connected to the slide 22 which arm advances it into alinement with the rams 4 and 6. At the subsequent movement of the rams, the ram 4 takes a knob 29 from the 105 end of the feeding channel 24 and forces said knob into the eye of the flap 32^a simultaneously with forcing the latter on the

hinge pin of the flap 32 which is disposed in the path. Finally the completed hinge is expelled from the machine by an arm 43, connected to a right-angled extension on the 5 arm 41, and deposited through an aperture 44 in the table top into a suitable receptacle. The arms 41 and 43 are disposed so as to keep clear of the flaps themselves and advance them by engagement with the eyes.

10 In order to secure the flaps firmly in position while the rams operate, the following arrangement is provided: A plate 35 is adapted to rock about a shaft 34, the rocking being effected by a cam 37 mounted on 15 the shaft 13 and coöperating with a spring 36. Lugs 33 and 42 on the free end of the plate are disposed so as to place themselves over the eyes of the hinge-flaps and prevent lateral movements of the same when the 20 plate is acted upon by the cam 37. This is done simultaneously with the operation of the rams. The engaging surfaces of the lugs are grooved, as shown in Fig. 3, to coincide with the eyes, a firm hold on the 25 flaps being thereby obtained. The paths followed by the various hinge-parts on the table, particularly those of the knobs 29 and of the pins 30, are also grooved so that no spontaneous movement of the elements takes place. The movements of the 30 rams and of the slides are regulated so that the hinge-parts are put through the various stages of the operation in due order. While the rams operate for connecting the parts 35 fed into alinement with the same, the arms 31 and 40 feed fresh flaps into reach of the slides 21 and 22. The slide 21, while feeding one flap into alinement with the rams 3 and 5, feeds the previous one into alinement with the rams 4 and 6 by means of its arm 38. Similarly, the slide 22, while feeding one flap, by means of its arm 41, into alinement with the rams 4 and 6, expels the 40 previously completed hinge from the machine by means of its arm 43. After the return movement of the rams and their arms, a fresh pin and fresh flaps and knobs are fed by the channels into operative position. In order to enable the elements to be 45 correctly adjusted and to adapt the machine for hinges of various sizes, the rams are connected to their holders by means of screws 46 passed through longitudinal slots 45. For the same purpose the slides 21 and 22 are connected to the levers 19 by means of 50 adjusting screws 47.

60 The described construction and combination of the elements may be modified within the scope of the appended claims without departing from the spirit of the invention. Machines of correspondingly modified construction may be used for the assembling of other kinds of hinges.

65 We claim:—

1. A machine for assembling the parts of

butt hinges and the like, comprising a table, inclined feeding channels for feeding the various hinge parts onto the table top, two pairs of horizontally movable co-axial rams arranged on the table top, one ram of each pair having an off-set arm adapted to move the lowest flap away from a feeding channel, a slide for moving one of the discharged flaps so that its eye gets into alinement with one pair of rams and for simultaneously 70 moving the flap previously operated upon by the rams into alinement with the other pair of rams, a slide for moving the flap discharged from the other channel into alinement with the second pair of rams and 75 for simultaneously expelling the completed hinge from the machine, means for guiding the hinge pin and knobs so that a pin and a knob are connected by the first pair of rams to one flap and so that another flap is 80 connected to the same pin and a knob to the other flap by the second pair of rams, shafts having eccentrics for operating the rams, cams at one end of the shafts, levers 85 acted upon by said cams for operating the slides, a driving shaft, and connections between said driving shaft and the aforementioned shafts for operating the latter, substantially as set forth.

2. A machine for assembling the parts of 95 butt hinges and the like, comprising a table, inclined feeding channels for feeding the various hinge parts onto the table top, two pairs of horizontally movable co-axial rams arranged on the table top, means for moving, at each operation of the rams, two hinge flaps away from their channels and for guiding each flap with its eye into alinement with a different pair of rams, the first pair of rams being adapted to take a hinge pin 100 and a knob and secure them to the flap arranged in alinement therewith, means for guiding said flap and pin into alinement with a second pair of rams, the latter being adapted to take a knob from its channel and 105 secure the same to the loose flap lying in alinement therewith as well as to secure the latter flap to the pin of the other flap, means for guiding the flaps laterally while acted upon by the rams, means for expelling the 110 completed hinge from the machine, a driving shaft, and connections between said driving shaft and the various parts of the machine for operating the same, substantially as set forth.

3. A machine for assembling the parts of 115 butt hinges and the like, comprising a table, inclined feeding channels for feeding the various hinge-parts onto the table top, two pairs of horizontally movable co-axial rams adapted to expel the lowermost hinge pin and the lowermost knobs from their channels and connect them to the eyes of the hinge flap, off-set arms on two rams for 120 expelling the flaps, slides for guiding the flaps 125 130

into alinement with the rams for guiding the flaps from the first to the second pair of rams and for expelling the completed hinge from the machine, eccentrics for actuating the rams, cams for operating the slides, a rocking plate, grooved lugs on said plate, a cam acting on the plate so as to apply the grooved lugs to the hinge eyes and guide the flaps laterally while the rams

operate, a driving shaft, and connections between said shaft, said eccentrics and said cams for operating the machine, substantially as set forth. 10
